UNITED STATES PATENT OFFICE.

FREDERICK W. GOYETTE, OF SAN FRANCISCO, CALIFORNIA.

AIRSHIP.

1,042,338.

Specification of Letters Patent.

Patented Oct. 22, 1912.

Application filed March 9, 1911. Serial No. 613,222.

To all whom it may concern:

Be it known that I, FREDERICK W. GOYETTE, a citizen of the United States, residing at San Francisco, in the county of 5 San Francisco and State of California, have invented new and useful Improvements in Airships, of which the following is a specification.

This invention relates to improvements in 10 air ships.

One object of the invention is to provide an air ship so constructed as to operate on the principle of a parachute, rendering it impossible for the machine to tip over in 15 any direction in mid-air, and thereby insuring the safety of the operator.

A further object is to provide improved means whereby the air ship can rise and descend with great safety.

20 A further object is to improve the mechanism for steering the air ship, and especially for so steering it while the motor is not in operation.

A further object is to provide an air ship, 25 which, when on water, can be used as a boat, and, when on land, can be operated as an automobile, and particularly to provide one in which, for this object, the wings may be collapsed, so that the size of the machine 30 can, when desired, be greatly reduced.

A further object is to provide an improved arrangement of propellers whereby the machine can be propelled in any direction desired, and also to provide an improved arrangement of said propellers whereby the propulsion may be more efficient than heretofore.

In the accompanying drawing, Figure 1 is a side view of the air ship; Fig. 2 is a 40 plan view thereof; Fig. 3 is a vertical section on the line 3—3 of Fig. 1.

Referring to the drawings, 1 indicates the engine of the air ship which may be of any desired construction, and 2 the shaft for 45 said engine. Said engine is contained within a hull 3, which is formed similarly to the hull of a boat, and is provided, if desired, with water-tight compartments. The shell of said hull is suitably strengthened at four 50 points, as shown at 4, to provide recesses 5, adapted to receive stems 6, which are normally depressed by springs 7 around said stems, said springs being compressed between the upper ends of the recesses and

collars 10 on said stems, said stems having 55 on their upper ends nuts 11 for limiting the downward movement of said stems. Said stems at their lower ends are connected to forks 12, and in the lower ends of the members of each fork is supported a shaft 13 60 carrying a wheel 14. The inner fork-members of the front wheels are connected to extensions 15, which are connected to a link 16, which, in turn, is connected to a crank arm 17 on a vertical shaft 20, which is supported in a suitable water-tight bearing 21 on the hull, said shaft being connected with a steering wheel 22. In this way the machine, when traveling on dry land, can be 65 steered in any direction.

70 The engine shaft passes through bearings 22 and has thereon a propeller 23 for propelling the machine when used as a boat. Upon the rear end of said shaft is secured a bevel gear 25 which meshes with a bevel 75 gear 26 on a vertical shaft 27 having at its upper end a bevel gear 28 which meshes with a bevel gear 29 on a horizontal longitudinal shaft 30, which has a bevel gear 31 meshing with a bevel gear 32 on a vertical 80 shaft 33, which carries at its upper end a lifting propeller 34. The vertical shaft 27 is provided with a bevel gear 35, which meshes with a vertical bevel gear 36, on a short horizontal shaft 37, which carries at 85 its rear end a bevel gear 38, meshing with a bevel gear 39, on a vertical shaft 40, the upper end of which shaft 40 carries a bevel gear 41, meshing with a bevel gear 42, on a horizontal shaft in a rear frame 43. The 90 construction and mode of operation of said rear frame 43 is precisely like that of a front frame 44, and the description of the latter will apply also to the former. I will therefore now describe the front frame and 95 the parts immediately connected therewith.

The engine shaft is connected by a universal joint 47 with a shaft 48, connected by a universal joint 49 with a shaft 50, having a bevel gear 51 meshing with a bevel gear 52 100 on a vertical shaft 53, the upper end of which carries a bevel gear 54, which meshes with a bevel gear 55 on a horizontal shaft 56 in said front frame 44. Said horizontal shaft 56 carries a bevel gear 57, which 105 meshes with a bevel gear 58 on a vertical shaft 59 which carries at its upper end a bevel gear 60, meshing with a bevel gear 61

on a horizontal shaft 62, which carries bevel gears 63, 64, meshing with bevel gears 65, 66, on the shafts of the propellers 67, 68. The horizontal shaft 62 and propeller shafts 5 are mounted in a revoluble frame 69 which is connected to a bevel gear 70 meshing with a bevel gear 71 upon a vertical shaft 72 carrying at its lower end a bevel gear 73 meshing with a bevel gear 74 on a horizontal 10 shaft 75 carrying at its other end a bevel gear 76 which meshes with a bevel gear 77 on a vertical shaft 78 carrying at its upper end a bevel gear 79 which meshes with a bevel gear 80 upon a tubular shaft 81 which 15 is turned by hand and controlled by a hand wheel 82. To said tube is also connected, as shown at 83, a tube 84 extending rearwardly and which operates a precisely similar mechanism of the frame 43 at the rear end of the 20 ship. Hence, by turning said hand wheel 82, both the propellers of each frame can be turned to operate in any direction desired. The shafts 56 and 75 at each end form 25 hinges or pivots upon which said frames 43, 44, can rock bodily from an upright to a lowered position and conversely.

The following is the object of this arrangement. The air ship is provided, in addition to the main central aeroplane 87, 30 with side planes 88, which are pivoted at their inner edges, as shown at 89, and are braced by braces 90, which are pivoted to rods 83 secured at their ends to collars 91 slidable vertically on posts 92. When the 35 propellers 67, 68, are set in motion their motive power causes said frames 43 and 44 to rock upward from their lower position to an elevated position, as shown in Fig. 3. In doing so, pins 93, extending laterally from said frames, and engaging the rods 83, automatically raise said planes to their elevated position. They may be further raised by the operator by means of cords 101 and when so raised may be secured in any suitable manner. The object 40 of this arrangement whereby said side planes are not moved into their upper position until automatically so raised by the rise of the frames due to the propellers, is as follows:—If said planes were so extended horizontally before the ship was clear of the waves, it might happen that, by the sudden impact of a wave, the ship would be tilted many degrees to one side, and the side aeroplanes would be immersed in the water. 45 By maintaining said side aeroplanes in a vertical position until the ship has a velocity sufficient to lift it from the water, the force tending to maintain it in an up-right position is as great as possible, and, when the ship rises from the water, the planes open in the proper time and the ship then takes a rapid upward flight. I also provide additional planes 94, 95, on the 50 sides of the ship which perform the func-

tion of a parachute when the ship is descending to the ground. These planes are suitably pivoted, as shown at 96, and are braced against upward movement by braces 97, connected to collars 98, 99, the upper 70 collars 98 being attached to tubes 100, which in turn are attached to cords 101 which pass around pulleys 102 and extend to any suitable part of the airship, from which they can be manipulated. The lower collars 99 are connected to the upper collars 98. Said lower planes 94, 95, when collapsed 75 form a protection for the sides of the ship, both when used in water and when used as an automobile. It is understood, of course, that the machine is primarily intended as an air ship and is used as a water ship or as an automobile only in cases of emergency. Both the front and rear frames 44, 43, are rotatable about their vertical 80 central axes on turn-tables 104 movable by any suitable mechanism.

Upon said shaft 56 is secured a bevel gear 57 which meshes with a bevel gear 112 on a horizontal shaft 113 the front end 90 of which carries a bevel gear 114 which meshes with a bevel gear 115 on a vertical shaft 116 passing through bearings 117 in a frame 118, which vertical shaft 116 has a bevel gear 119, which meshes with two 95 bevel gears 120, 121, on shafts 122, 123, in line with one another in said frame, the front shaft 122 carrying a propeller 124, and the rear shaft 123 carrying a rear oppositely rotating propeller 125. The object 100 of providing these oppositely rotating propellers is that the front propeller may deflect the air and causes it to flow in a direction very advantageous for obtaining power therefrom by means of the rear propeller, 105 and also for the purpose of maintaining equilibrium between the two turning movements produced thereby at the front end of the ship, and to reduce the rotary effect upon the ship which is produced by one 110 propeller. To said frame is secured a bevel gear 130 which meshes with a bevel pinion 131 on a steering shaft 132 which extends the length of the ship, being secured to a steering wheel 133. Said steering shaft has 115 at its rear end a bevel gear 134 which meshes with a bevel gear 135 on a vertical shaft 136 having upper and lower bearings 137, 138, supported by extensions from the frame 120 of the ship. To said shaft 136 is secured a steering rudder 140 for steering the air ship in any desired direction laterally. On turning the steering wheel 133 the shaft 132 is turned so that the bevel gears 131 and 134 at the respective ends of the ship turn 125 the bevel gears 130 and 135 so that the propeller frame at the front of the ship is inclined to one side of the longitudinal vertical plane of the ship and the rudder 140 is inclined to the other side thereof, so that 130

they coöperate in steering the ship. To the lower end of said vertical shaft 136 is secured a gear wheel 141 which meshes with a segment gear 142 connected to a rudder 143 for steering the machine when used as a boat.

At the front and rear of the air ship, at the sides thereof, are provided aeroplanes 150 which can be turned about horizontal axes, to any desired inclination to the horizon, by means of arms 151 attached to the shafts of said aeroplanes and operated by cords leading to the ends of arms 155 secured to a worm wheel 154 operated by a worm 156 upon the tubular shaft 81. Said cords may also be attached to the shaft upon which the frames swing, so that said aeroplanes can also be turned at the same time with said frames.

20 The hull is made with water-tight and air-tight compartments. As such water-tight compartments are common in marine vessels, their illustration is not here needed. These compartments may be filled with hydrogen or other light gas if desired, since 25 the weight of the engine will still be sufficient to counteract the buoyant effect of said compartments.

I claim:—

30 1. The combination with the frame of an air ship of a vertical rod, a tube slidable thereon, a collar connected to the lower end of said tube, a brace depending from said collar, an aeroplane to which the lower end 35 of the brace is connected, a second collar slidable upon the rod connected to the inner edge of the aeroplane, a brace depending from said second collar, a second aeroplane connected to the lower end of said brace, 40 the inner edge of said latter aeroplane having pivotal connection with the frame of the ship.

2. The combination with the frame of an air ship of a vertical rod, a tube slidable 45 thereon, a collar connected to the lower end of said tube, a brace depending from said collar, an aeroplane to which the lower end of the brace is connected, a second collar slidable upon the rod connected to the inner 50 edge of the aeroplane, a brace depending from said second collar, a second aeroplane connected to the lower end of said brace, the inner edge of said latter aeroplane having pivotal connection with the frame of the 55 ship, a collar secured to the upper end of the tube, a brace the inner end of which is pivoted to said collar, an aeroplane the inner edge of which is pivotally connected to said rod, the upper end of said latter 60 brace being pivotally connected to said latter aeroplane.

3. In an air-ship, the combination of a vertical rod, a tube slidable thereon, collars attached to the ends of said tube, an 65 aeroplane the inner edge of which is piv-

otally connected to said rod, an oblique brace connected to said aeroplane and to the upper collar, a collar slidable upon the rod below said tube, an aeroplane the inner edge of which is connected to said latter 70 collar, a brace connected to said latter aeroplane and to the lower collar on the tube, an aeroplane the inner edge of which has pivoted connections with the rod, a brace connected with said latter aeroplane and 75 the lowermost collar, and a cord connecting said latter collar with the lower-most collar on the tube.

4. In an air ship, the combination of a vertically extending propeller frame, a shaft 80 extending vertically through said frame, horizontal propeller shafts mounted in opposite sides of the propeller frame, means whereby said propeller shafts are operatively connected to said first-named shaft 85 to be rotated thereby in opposite direction, propellers on said propeller shafts, means for rotating said first-named shaft, and means for rotating said propeller frame about a vertical axis. 90

5. In an air ship, the combination of a propeller frame at an end of the ship, a horizontal propeller shaft mounted therein, a propeller on said shaft, a vertical shaft extending through said propeller frame and 95 operatively connected with said horizontal propeller shaft, means for rotating said vertical shaft, a rudder at the other end of the frame, a vertical shaft upon which said rudder is mounted, a shaft extending the full 100 length of the ship, means for turning said shaft, and operative connections between the ends of said shaft and the propeller frame at one end of the ship, and the rudder shaft at the other end of the ship, whereby, by 105 rotation of said shaft, said propeller frame and rudder shaft are rotated in opposite directions.

6. In an air ship, the combination of a transversely extending propeller frame, a 110 horizontal shaft mounted in said frame, propeller shafts mounted in said frame at right angles to said horizontal shaft and operatively connected thereto, means at one end of the frame for rotating said horizontal shaft and means at the other end of the frame for rotating the frame about a central horizontal axis. 115

7. In an air-ship, the combination of a transversely extending propeller frame, 120 transversely extending horizontal pivots adjacent to the deck of the ship, supports connected at one end to the ends of said frame and at the other end pivotally connected to said pivots whereby said transversely extending frame may be swung upon said pivots as an axis, a horizontal shaft mounted in said propeller frame, propeller shafts mounted in said frame at right angles to 125 said horizontal shaft, and operatively connected 130 to said horizontal shaft, and operatively con-

nected thereto, propellers thereon, and operative connections whereby by the rotation of one of said pivots the propeller frame may be rotated about its axis and by rotation of the other pivot the horizontal shaft and the propeller shafts may be rotated.

5 In testimony whereof I have hereunto

set my hand in the presence of two subscribing witnesses.
